HOSIERY

Norman Cohn, New Rochelle, N. Y.

Application December 19, 1936, Serial No. 116,683

4 Claims. (Cl. 66—173)

The invention relates to garter top hosiery of the type in which an elastic garter is positioned in the welt or top portion of a sock and the invention relates to an improved method for forming such types of socks.

More specifically defined the invention relates to a method for facilitating the sewing in place of the turned-over top welt or cuff forming portion to secure a smooth, pleasing line of sewing and of most serious import to provide a more rugged and secure attaching of the free edge of the turned over portion than has been possible heretofore with similar constructions.

Still another object of the invention and supplementing the mechanical or structural features, is to provide a more artistic and pleasing form of turned-over welt than has been known heretofore in hosiery having a seamless ribbed knitted top portion and in which aspect the invention relates to hosiery in general and not necessarily restricted to those with built-in garters.

Various other objects and advantages of the invention will be in part obvious from a consideration of the method features of the disclosure and from an inspection of the accompanying drawing and in part will be more fully set forth in the following particular description of one method of practicing the invention, and the invention also consists in certain new and novel modifications of the preferred method and other features of construction and combination of parts hereinafter set forth and claimed.

In the accompanying drawing:

Fig. 1 is a view in side elevation of the upper portion of a child's sock of the seamless knitted type illustrating the step of inserting the garter in place before the welt or cuff is turned;

Fig. 2 is a view similar to Fig. 1 with the welt turned thus illustrating a succeeding step in the method herein featured and showing parts broken away to disclose normally concealed parts;

Fig. 3 is a similar view of the completed hose; and

Fig. 4 is an enlarged fragmentary view of several of the courses of the knitting adjacent the juncture line between the body portion and the top portion of the structure shown in the preceding figure.

In the drawing there is shown a seamless knitted body portion 10 formed conventionally of courses 11 and also following conventional practices usually made of fine gauge material. The top of the stocking is formed of a seamless ribbed knitted top portion 12 knitted for the most part of courses 13 and which again following conven-

tional practices is formed of a relatively heavier yarn than the yarn used in the body portion 10. While the invention is specifically described herein with reference to its application to hosiery where the body portion 10 is a seamless knitted portion and the top portion 12 is a seamless rib-knitted portion, it is within the scope of the disclosure to otherwise differently knit these two portions, as by a continuous knitting operation where the body may be either plain or ribbed knitting, and in which case the line 19 would form simply a line of demarcation between the two portions rather than a distinctive connecting course.

It is a feature of this disclosure that one or more welt lines are knitted into the fabric forming the top portion. In the illustrated embodiment of the invention four such welt lines are formed in two groups of which three lines 14, 15, 16 are knitted into the top portion adjacent the edge 17 which is knitted to the body portion 10 through the line of juncture 18 defined by the usual loose course 19. The fourth welt line 20 is knitted approximately mid-height of the top portion as shown in Fig. 1, or approximately mid-length between the band provided with the three closely positioned lines 14—15—16 and the free edge of the top portion. These welt lines are formed in any known manner for showing a course visually distinctive from the courses forming the balance of the top portion. For instance, the welt lines may be formed by fancy stitches, by stitches of the type usually used to reinforce as by the use of ingrain yarn or by using a yarn which may or may not have reinforcing capacity but which is tinted or colored in some manner distinctive in color from the yarn used to form the balance of the top portion.

With the stocking thus constructed with its tubular top portion upstanding as shown in Fig. 1, an endless band garter 21 is placed to encircle the top portion approximately centered between the welt lines 16 and 20, it being understood that at this stage of the proceedings the stocking as a whole is turned inside-out. The top free edge 22 is then folded outwardly and downwardly over the garter 21 as indicated by the arrow in Fig. 1 and into the dotted line position. In this folding operation the top welt line 20 may be conveniently utilized to locate the fold 23 forming the upper edge of the finished sock. As it is herein suggested that the welt line 20 be utilized as part of the decorative scheme of the disclosure, the upper portion of the stocking will be turned back close to, but spaced from and parallel to the line 20

so that the line will be visible on the outer side of the top portion as shown in Fig. 3.

It is a feature of this disclosure that the free edge 22 be secured to the seamless ribbed top portion by a line of sewing 24 sometimes herein referred to as a securing line which is within the more rugged body of the top portion rather than at the loose course 19. In the specific form of the invention herein disclosed, the stitching 24

10 is confined to the area reinforced by the band formed by the welt lines 14, 15 and 16. This reinforcement may be attached by any conventional practice such as by using a heavier thread in the courses 14, 15 and 16 or by an additional 15 thread plated in these courses. In such case the welt lines, or any one of them, provide a convenient guide for assisting the operator in locating the sewing 24 and thus, of course, locating the lower edge 22 in position parallel to, but 20 spaced from, the juncture line 17 so as to leave therebetween a narrow band 25 of the rugged material of which the top portion is formed. This means that the sewing threads engage in a portion of the ribbed top which is particularly 25 reinforced and strengthened for this purpose as the stitches have more material to engage than if the stitching was along the thinned out portion of material which forms the loose course at 19. It is further suggested that the stitches at 24 be 30 blind stitches so as to minimize the showing of the stitches on the outside of the stocking top. As it is difficult, if not impossible, to prevent at least some of the stitches from extending through and thus showing on the outside of the 35 stocking top, the welt line construction herein featured tends to conceal and hide any such stitches which may come through, even in the cases where the so-called blind stitching is utilized.

40 The three lines of courses 14, 15 and 16, are suggested as preferable over a single line at this point because the three lines provide a more easily followable gauge line for the operator than the single line and from an artistic standpoint, the three closely positioned guide lines provide a 45 most pleasing appearance to what would be otherwise an unbroken vertical striped effect provided by rib topped hosiery. The sewing operator is instructed to locate the line of sewing along the middle line 15 and to keep the sewing 50 away from the border lines 14 and 16. He is apparently better able to follow a straight course of sewing than if he had to follow a single guide line.

55 The addition of these welt lines does not interfere with the desired elasticity of the ribbed top portion and this top portion is free to expand and contract with the garter. While the garter is restrained from any material movement in the 60 pocket formed by the double layer of material at the top of the stocking, it is entirely free to move relative to the top portion and no binding action takes place between the garter and stocking.

65 Insofar as outward appearance is concerned, there is disclosed simply the usual loose course juncture line, 18, then within the body of the ribbed structure forming the elastic top three closely arranged parallel welt lines 14-16 and adjacent the top of the hose a single welt line 70 20, all tending to break up the long parallel ribs and providing a pleasing form of top to the hose and which does not disclose any evidence that there is a garter contained in the cuff.

While there have been shown, described and pointed out in the annexed claims, certain novel features of the invention, it will be understood that various omissions, substitutions and changes in the form and details of the described hose and in its construction may be made by those skilled in the art without departing from the spirit of the invention. 5

I claim:

1. In the art of forming garter top socks, the 10 method which consists in knitting a seamless ribbed top portion with four courses visibly distinctive from the others, three of said courses being in juxtaposition to form a reinforced narrow band and the other course being spaced from said 15 band, knitting a seamless body portion to the top portion with the reinforced band adjacent to and spaced from the body portion, placing an endless garter on the part of the top portion between the reinforced band and the other distinctive 20 course line, folding the free edge of the top portion back upon itself over the garter using said other distinctive course line as a guide to indicate the location of the bend which is to form the top of the sock, and stitching the free down-turned end to the reinforced area and particularly to the middle of the three distinctive courses while utilizing said three courses as a guide during 25 the sewing operation.

2. In the art of forming turned top hosiery, the 30 method which consists in knitting a seamless ribbed knitted top portion with one interior course thereof visibly distinctive and contrasting from the others, knitting a plain seamless knitted body portion to the top portion along a juncture line, folding the free edge of the top portion back upon itself until said free edge is at the distinctive line and spaced from the juncture line, and stitching said free edge to said distinctive 35 course while utilizing said distinctive course as a guide during the sewing operation, leaving a band of single thickness of ribbed material between the plain body portion and the double thickness of material at the top of the hosiery. 40

3. A sock having a seamless knitted body portion and a seamless ribbed knitted top portion with one interior course thereof visibly distinctive and contrasting with the other, said portions being knitted together along a juncture line, the top portion comprising a single layer of material, bent back upon itself to the distinctive course to form solely a double thickness of material at the upper end of the sock and a single thickness of ribbed material between the double thickness and the juncture line, the lower edge of the bent back portion secured directly to the single layer ribbed portion along the distinctive line in said single layer extending parallel to and spaced from the juncture line. 45

4. A sock having a seamless knitted body portion and a seamless ribbed knitted top portion, said portions knitted together along a juncture line defined by a loose course, one course of the ribbed top portion providing a line of reinforcement spaced from said loose course, said top portion being bent back upon itself to form a double thickness of material at the top of the sock and the turned back edge secured to the ribbed top portion along said line of reinforcement and thus spaced from said juncture line. 50
